UNITED STATES PATENT OFFICE.

WILLIAM W. BALL, OF INDIANAPOLIS, INDIANA, ASSIGNOR OF ONE-HALF
TO ADDISON W. BALL, OF SAME PLACE.

BUGGY-SEAT.

SPECIFICATION forming part of Letters Patent No. 295,143, dated March 18, 1884.

Application filed January 9, 1884. (No model.)

To all whom it may concern:

Be it known that I, WILLIAM W. BALL, of the city of Indianapolis, county of Marion, and State of Indiana, have invented certain new and useful Improvements in Buggy-Seats, of which the following is a specification.

My said invention principally consists in an improved corner-piece for buggy-seats, by which the corner is protected and the sides and back of the seat securely fastened to the bottom.

It further consists in an improved means for securing the shifting-rail to the seat, consisting of ears on said corner-piece and other similar supports.

My said invention will be first fully described, and then pointed out in the claims.

Referring to the accompanying drawings, which are made a part hereof, and on which similar letters of reference indicate similar parts, Figure 1 is a perspective view of a seat embodying my said invention; Fig. 2, a top or plan view thereof, a portion being broken away at one corner to show the corner-piece more plainly; Fig. 3, a diagonal vertical section on the dotted line *z z*, and Fig. 4 a perspective view of the corner-piece separately.

In said drawings, the portions marked A represent the bottom of the seat; B, the sides and back; C, my improved corner-piece, and D the shifting-rail.

The bottom A and sides and back B are similar to the corresponding parts in ordinary carriage-seats, and need no special description.

The corner-pieces C are of a peculiar formation. The lower end is spread out and formed to fit over the corner of the bottom A, to which it is attached by screws, as shown, and is thus both firmly attached thereto and serves to secure said corner together. They are then en-smealed and extend up in the form of angle-irons around the outside of the corners, where the back and sides come together, securing said parts firmly, and serving as a protection therefor after the seat is finished. The top ends are spread out into ears c', one of which on each is hooked to pass under the rail D and the other to pass over it, thus securing said rail at the corners without other fastenings.

These ears should also extend down alongside

the back and sides a short distance, and thus be adapted to be secured to said back and sides by screws or rivets *c*. These corner-pieces, besides serving the aforementioned purposes, are great aids during the process of building 55 the seat, as, after being secured to the bottom, they are adapted to hold the sides and back in place while the latter are being fastened, without the aid of the usual clamps or stays, it being only necessary to fit said back and sides 6c and place them in position inside of said corner-pieces, when, as will be readily seen, they will be sufficiently held in position to enable the workman to fasten them without difficulty.

The rail D is formed of a single rod carried 65 from the front edge of one side of the seat around the top of the sides and back to a corresponding point on the other side, passing through the hooks on the corner-pieces C and through other hooks, *b*, on the back B, and being thus supported. At the ends it is turned up at right angles and screw-threaded, and these turned-up ends pass up through eyes in projecting ends of the angle-irons *b'* or similar parts, and have nuts *d* on their ends. By simply removing these nuts and springing the ends of the rail down, said rail can be readily detached from the seat, which is a much simpler operation than removing the numerous 75 bolts and screws usually employed to secure 80 these rails.

Having thus fully described my said invention, what I claim as new, and desire to secure by Letters Patent, is—

1. The combination, with the bottom, sides, 85 and back of a buggy-seat, of corner-pieces C, which cover the corners of said sides and back and extend under the same over the corners of said bottom, and thus secure the parts of the seat together and protect the corners of the 90 same, substantially as set forth.

2. The combination, with the bottom, sides, and back of a buggy-seat, of corner-pieces widened at the lower end and formed to cover the corners of said bottom and be secured thereto, 95 and extend thence up over the outside of the corners of the back and sides, substantially as described, and for the purposes specified.

3. In a buggy-seat, a corner-piece, C, having ears c', formed into hooks to support the 100

shifting-rail, in combination with said rail, substantially as set forth.

4. The combination of the usual seat parts, the shifting-rail, and a series of hooks on the seat ass supports for said rail, parts of said hooks being curved to pass under said rail and a part over it, thus securing it firmly in position without the use of other fastenings, except at the ends, substantially as set forth.

15 5. The combination of the ordinary seat parts, A B, the corner-pieces thereon, provided with

hooks, and the shifting-rail mounted in said hooks, and thus secured in position, substantially as set forth.

In witness whereof I have hereunto set my 15 hand and seal, at Indianapolis, Indiana, this 4th day of January, A. D. 1884.

WILLIAM W. BALL. [L. S.]

In presence of—

C. BRADFORD,
CHAS. L. THURBER.
